Patented Nov. 22, 1921.

Inventor
SAMUEL N. HURT.

By Comer Marshall Attorney

UNITED STATES PATENT OFFICE.

SAMUEL N. HURT, OF TOLEDO, OHIO, ASSIGNOR TO TOLEDO SCALE COMPANY, OF TOLEDO, OHIO, A CORPORATION OF NEW JERSEY.

WEIGHING-SCALE.

1,397,521.

Specification of Letters Patent. Patented Nov. 22, 1921.

Application filed December 27, 1920. Serial No. 433,136.

To all whom it may concern:

Be it known that I, SAMUEL N. HURT, a citizen of the United States, residing at Toledo, in the county of Lucas and State of Ohio, have invented certain new and useful Improvements in Weighing-Scales, of which the following is a specification.

This invention relates to weighing scales, and one of its principal objects is to provide reliable and inexpensive means for securing a pivot in place upon a scale lever.

Another object is to provide means for so securing a pivot to a lever that it may be readily removed or replaced.

Still another object is to provide means whereby the distances between pivots may be very accurately adjusted.

Other objects and advantages will be apparent from the following description, wherein reference is had to the accompanying drawings illustrating preferred embodiments of my invention and wherein similar reference numerals designate similar parts throughout the several views.

In the drawings:—

Figure 1 is a fragmentary elevation of a lever showing preferred means for securing knife-edge pivots of the usual shape;

Fig. 2 is a fragmentary elevation of a lever showing means for securing another form thereof; and

Fig. 3 is an enlarged perspective view of the pivot bar employed in the form shown in Fig. 2.

Although I have shown my pivot retainer in connection with a lever, it is to be understood that it is also capable of use in securing pivots to other members, such, for example, as pendulums or stationary supports.

In the embodiment illustrated in Fig. 1, the nose of the lever 1 is provided with a transverse cylindrical bore 2 into which are tapped two threaded holes 3 leading from the lower side of the lever. The pivot retainer

in this embodiment consists of a bar 4 having cylindrical surfaces at its sides which substantially fit the sides of the bore 2. In the upper side of the bar 4 is a V-shaped groove 5, the apex of which is at the center of curvature of the cylindrical surfaces, and the lower side of the bar is substantially flat, with a kerf 6 extending upwardly toward the groove 5.

When the pivot bar 7, which is of the

usual wedge shape, is inserted in the groove 5, the knife edge of the pivot in this form of the device is substantially coincident with the axis of the bore 2, so that if the retainer 4 is rotated slightly in the bore, the location of the knife edge will not change. Set screws 8 and 9 are threaded into the holes 3 and forcibly engage with the flat lower side of the retainer 4 which, because of the comparatively small amount of metal between the kerf 6 and the apex of the groove 5, is deformed by the pressure of the screw, the kerf opening slightly and the sides of the groove being forced into clamping engagement with the sides of the wedge-shaped pivot 7. The pivot is thus firmly held in place, but it may nevertheless be easily removed when desired.

The form shown in Fig. 2 differs from that shown in Fig. 1 in that the pivot retainer 4^a is provided with a bore 5^a to receive a cylindrical pivot bar 7^a which is cut away at its ends to form wedge-shaped pivots 10^a. A kerf 11^a is cut from the outside of the retainer 4^a into the bore 5^a so that when the pivot bar is in the bore and the retainer is in place, the bar may be securely clamped in the same manner as the wedge-shaped bar in the form first described by turning up the screws 8^a and 9^a and thus to some extent opening the inner kerf 6^a and closing the outer kerf 11^a.

The knife edge of the pivot in this form is radially spaced from the axis of the bore 2^a so that by rotating the retainer in the bore the pivot may be moved toward or away from the end of the lever. This movement, of course, cant the wedge-shaped pivots 10^a to some extent, but they may be righted by turning the pivot bars 7^a in the bores 5^a before finally tightening the screws 8^a and 9^a. Slight adjustments may be made by merely loosening one screw and tightening the other.

While it will be apparent that the illustrated embodiments of my invention herein disclosed are well calculated to adequately fulfil the objects primarily stated, it is to be understood that the invention is susceptible to variation, modification and change within the spirit and scope of the subjoined claims.

Having described my invention, I claim:

1. In a device of the class described, in combination, a member having a bore therein, a pivot, a pivot retainer mounted in said bore, said pivot retainer having a recess

adapted to receive the pivot, and means for deforming said pivot retainer to clamp said pivot in said recess.

2. In a device of the class described, in combination, a member having a bore therein, a pivot, a pivot retainer in said bore, said pivot retainer having a recess in one side thereof adapted to receive the pivot and a kerf in its opposite side, and means to deform said retainer to clamp said pivot in said recess.

3. In a device of the class described, in combination, a member having a bore therein, a pivot, a pivot retainer in said bore, said pivot retainer having a recess to receive the pivot and having a flat surface and a kerf extending from said flat surface toward said recess, and screws threaded through said member and engaging the flat surface of said pivot retainer on opposite sides of said kerf.

4. In a device of the class described, in combination, a member having a bore therein, a pivot bar, a pivot retainer in said bore, said pivot retainer having a substantially cylindrical recess to receive the pivot bar

and an opening from said recess through the side of said member, said member also having a flat surface opposite said opening and a kerf extending from said flat surface toward said recess, and screws threaded through said member and engaging the flat surface of said pivot retainer on opposite sides of said kerf.

5. In a device of the class described, in combination, a lever, a pivot retainer adjustably mounted therein, a pivot bar adjustably mounted in said pivot retainer, and means for simultaneously locking said pivot bar and pivot retainer in adjusted positions.

6. In a device of the class described, in combination, a lever, a pivot retainer rotatably adjustable in said lever, a pivot bar eccentrically mounted in said pivot retainer and rotatably adjustable therein, and means for simultaneously locking said pivot retainer and said pivot bar in adjusted positions.

SAMUEL N. HURT.
